Patented Sept. 30, 1919.

2 SHEETS—SHEET 2.

The drawing consists of two parts, Fig. 3 and Fig. 4, illustrating a mechanical assembly. Fig. 3 shows a top-down view of a rectangular base 20 with a central slot 21. A vertical support 22 is positioned in the slot, and a horizontal beam 23 is attached to its top. A vertical plate 24 is mounted on the beam 23. A central vertical column 25 is supported by the plate 24. A horizontal beam 26 is attached to the top of the column 25. A vertical plate 27 is attached to the top of the beam 26. Fig. 4 shows a side view of the assembly. It features a base 30 with a central slot 31. A vertical support 28 is positioned in the slot, and a horizontal beam 29 is attached to its top. A vertical plate 27 is attached to the top of the beam 29. A central vertical column 30 is supported by the plate 27. A horizontal beam 31 is attached to the top of the column 30.

UNITED STATES PATENT OFFICE.

FREDERICK I. SMITH, OF SIDMAN, PENNSYLVANIA.

SEESAW.

1,317,231.

Specification of Letters Patent. Patented Sept. 30, 1919.

Application filed March 31, 1919. Serial No. 286,287.

To all whom it may concern:

Be it known that I, FREDERICK I. SMITH, a citizen of the United States, residing at Sidman, in the county of Cambria and State 5 of Pennsylvania, have invented certain new and useful Improvements in Seesaws, of which the following is a specification, reference being had to the accompanying drawings.

10 This invention relates to an improved indoor see-saw for children, and the aim of this invention is to provide a simple, efficient and practical indoor apparatus of this kind, whereby considerable amusement can be 15 afforded for children.

The invention further aims to provide improved means whereby the see-saw board may be fulcrumed upon a pedestal, which is portable from one place to another.

20 The invention further aims to provide a see-saw having means, for instance such as an adjustable weight, whereby one end or the other of the board may be counter-balanced, relatively to the child, or person on 25 the other end of the board, and in this way, the see-saw may be operated by a single individual.

A further object of the invention is to 30 provide a see-saw, in which the counter-balancing weight can be adjusted toward and from the fulcrum of the board, whereby children of different weights may actuate the see-saw.

A further object of the invention is the 35 provision of means for holding the counter-balancing member or weight on one end of the board with sufficient firmness to prevent its displacement, while the board is in action.

40 While the design and construction at present illustrated and set forth is deemed preferable, it is obvious that as a result of a reduction of the invention to a more practical form for commercial purposes, the invention 45 may be susceptible to changes, and the right to these changes is claimed, provided they are comprehended within the scope of what is claimed.

The invention comprises further features 50 and combination of parts, as will be herein-after set forth, shown in the drawings and claimed.

In the drawings:

55 Figure 1 is a perspective view of a seesaw apparatus constructed in accordance with the invention.

Fig. 2 is a longitudinal sectional view showing differently constructed handles than that illustrated in Fig. 1, in fact, the handles in this figure consist of uprights 60 and a transverse crossbar connecting the upper end of the upright, while in Fig. 1 the handles are U or arch shaped.

Fig. 3 is a transverse sectional view on line 3—3 of Fig. 2, that is vertically through 65 the pedestal and transversely through the center of the board, where it is fulcrumed on the pedestal.

Fig. 4 is a transverse sectional view through one end of the board showing the 70 means for strapping the weight or counter-balancing member to the board.

Fig. 5 is a perspective view of a modified construction of a see-saw, in which T-shaped handles rise upwardly from the see-saw 75 board.

Referring more especially to the drawings 1 designates a suitable base, which may be constructed of any suitable material, and may be any general contour found suitable 80 for the purpose. Rising upwardly from the base is a pedestal 2, which comprises the body 3 and the brace blocks 4, which are fastened by any suitable means, as shown at 5, to the body and the base, the brace blocks 85 being positioned as illustrated. The upper end of the body adjacent its opposite side edges has suitable bearing lugs 6, provided with axially aligned openings or bearings 7, in which a rod 8 is mounted. The pedestal 90 or base and the brace block may be constructed preferably of wood. The rod may be either wood or metal. In case it is constructed of wood, ordinary nails or the like may be driven through the same, adjacent 95 the inner faces of the bearing lugs, there being suitable washers 10 between the nails and the inner faces of the lugs. Should the rod be constructed of metal, it may be provided with apertures 11, for the reception of 100 cotter pins 12. Also in this case, suitable washers may be interposed between the cotter pins and the adjacent faces of the bearing lugs. It is to be noted that the rod is constructed of a length, whereby its opposite ends may project beyond the outer faces of the bearing lugs, thereby constituting 105 trunnions.

A see saw board 14 is supplied, and this board may be constructed preferably of wood 110 and may have any suitable design or configuration. Rising upwardly from the board

on opposite sides of the central portion thereof are suitable handles 15. These handles may be T-shaped as shown in Fig. 5, or may consist of uprights 16 connected by transverse pieces 17, or each handle may be constructed of a single piece arranged U-shaped, in fact, arched. In either case, however, the handles are provided for the purpose of being engaged by the hands, in order to steady and keep the individual on either end of the board from accidentally falling off the board, while the same is in motion.

Suitable bearing boxes 18 are secured by screws or the like 19 to the underface of the board. These bearing boxes are of the shape shown, and the depending parts 20 thereof are hollowed out U-shaped, as shown at 21. The depending parts, however, are provided with end walls 22, which engage the ends of the trunnions, thereby preventing lateral movement of the board relatively to the rod. The depending parts of the bearing boxes engage or move adjacent the outer faces of the bearing lugs, to further assist in holding the board in position. The bearing boxes may be constructed of wood, if found practical, but preferably they are designed to be constructed of metal.

As shown in the drawings means is provided in order to counter-balance a single individual on one end of the board. This means comprises a fixed bearing 23 adjacent the center of the board, said bearing being secured by suitable screws or the like 24. A rod 25 engages an opening 26 in the bearing 23, there being a set screw for holding this rod in different adjusted positions. On one end of the rod a counter-balancing member or weight 27 is mounted. If desired, this member 27 may be made a fixed part of the rod, or threaded on the rod if so desired. If threaded, it is obvious that the counter-balancing member or weight may be adjusted on the rod instead of adjusting the rod. It is obvious that the counter-balancing member or weight is employed to counter-balance the individual on the other end of the board. In this manner a single child can operate the see-saw as conveniently as when two operate it. The opposite sides of the counter-balancing member or weight is provided with depressions, which may be gouged out or otherwise formed and extending across the depressions 28 and integrally connecting the end wall of said depressions, are transverse pieces 29. Suitable straps 30 are connected to the transverse pieces 29, and the opposite ends of these straps are fastened together beneath the board, by means of a suitable buckle or the like 31. It is apparent that these straps may be drawn tightly together, and hold the counter-balancing member in contact with the board, instead of depending upon the secur-

ity of the set screw used in the bearings 23. By adjusting the counter-balancing member toward the center of the board, a child or light weight may operate the board. When the counter-balancing member is adjusted toward the outer end of the rod, a child or heavier weight may operate the board.

The invention having been set forth, what is claimed as new and useful is:

1. The combination with a pedestal having a base, the upper end of the pedestal having oppositely arranged upstanding lugs having axially aligned openings, of a rod arranged through said openings, whereby it is disposed transversely of the pedestal and having its ends projecting laterally beyond the lugs, thereby providing trunnions, a see-saw board, the under face of which being provided with bearing boxes provided with hollowed out U-shaped portions axially aligned and engaging said trunnions, washers on said rod respectively in contact with the adjacent ends of the upstanding lugs of the pedestal, retaining pins extending transversely of the rod and arranged in close position to the adjacent faces of the washers, to hold the washers in place, and to prevent axial movement of the rod, and oppositely arranged handles projecting from the upper surface of the board to be grasped for holding the persons on the opposite ends of the board.

2. The combination with a pedestal provided with a transverse rod having its opposite ends projecting beyond the opposite edges of the pedestal, thereby providing trunnions, of a board having bearing boxes adjacent its opposite side edges on the bottom surface of the board near its center engaging the trunnions, the upper surface of the board having upright handles, and means mounted upon the board for counter-balancing a single individual on the other end of the board, said means comprising a bearing centrally of the board, a weight provided with a rod passing through the last named bearing, and means for holding the rod adjustably in the bearing.

3. The combination with a pedestal provided with a transverse rod having its opposite ends projecting beyond the opposite edges of the pedestal, thereby providing trunnions, of a board having bearing boxes adjacent its opposite side edges on the bottom surface of the board near its center engaging the trunnions, the upper surface of the board having upright handles, and means mounted upon the board for counter-balancing a single individual on the other end of the board, said means comprising a bearing on the part centrally thereof, a rod mounted in the bearing fixedly, and a counter-poise member or weight adjustable on the rod.

4. The combination with a pedestal pro-

- vided with a transverse rod having its opposite ends projecting beyond the opposite edges of the pedestal, thereby providing trunnions, of a board having bearing boxes 5 adjacent its opposite side edges on the bottom surface of the board near its center engaging the trunnions, the upper surface of the board having upright handles, and means mounted upon the board for counter- 10 balancing a single individual on the other end of the board, said means comprising a bearing centrally of the board, a weight provided with a rod passing through the last named bearing, and means for holding 15 the rod adjustably in the bearing, and means for strapping the counter-balancing member or weight securely to the board
5. The combination with a pedestal provided with a transverse rod having its opposite ends projecting beyond the opposite edges of the pedestal, thereby providing trunnions, of a board having bearing boxes 20 adjacent its opposite side edges on the bottom surface of the board near its center engaging the trunnions, the upper surface of the board having upright handles, means mounted upon the board for counter-balancing a single individual on the other end of the board, said means comprising a bearing 25 on the part centrally thereof, a rod mounted in the bearing fixedly, and a counter-poise member or weight adjustable on the rod, and means for strapping the counter-balancing member or weight securely to the 30 board.
6. The combination with a pedestal, the 35 upper part of which having upwardly extending bearing lugs spaced, a rod engaging said bearing lugs, means carried by the rod adjacent the inner faces of the bearing 40 lugs to prevent axial movement of the rod, said rod having its ends protruding beyond the outerfaces of the bearing lugs, thereby providing trunnions, a see-saw board having means on its underface near its center 45 engaging the opposite trunnions, handles rising upwardly from the board and being centrally disposed, and means adjustable on the board and overhanging one end thereof, whereby a single individual on the other end 50 of the board may be counter-balanced.
7. The combination with a pedestal having a base, the upper part of the pedestal having oppositely arranged upstanding lugs, provided with axially alined openings, of a 55 rod arranged through said openings transversely of the pedestal, and having its ends projecting laterally beyond the lugs, of means on the rod arranged in close position to the adjacent faces of the lugs to prevent 60 axial movement of the rod, a see-saw board having bearing boxes, provided on their under parts with hollowed out portions to removably engage the trunnions, for fulcruming the board, and handles rising upwardly 65 from the upper surface of the board.

In testimony whereof I hereunto affix my signature in the presence of two witnesses.

FREDERICK I. SMITH.
